ORLEY C. HOUGHTON, OF RACINE, WISCONSIN

DISTRIBUTING APPARATUS

Application filed December 5, 1930. Serial No. 500,264.

My invention refers to distributing apparatus in general, and it is particularly applicable to silos wherein the cut feed is distributed into the silo and, by various means, distributed as near as possible uniformly.

My invention is particularly directed to automatic means for distributing material, such for example, as leaves and corn, the mechanism employed being such that the heavy and light articles of feed are evenly distributed throughout the entire surface, whereby excessive loss in silage is eliminated.

A further object of the invention is to provide, in connection with the standard delivery chute, a blade or deflector associated with the mouth of the chute in such manner that said deflector is mechanically rotated about the axis of the chute, and its position during such rotation, is also shifted radially, whereby an even distribution of the feed is effected.

Another object of my invention is to provide an impeller means associated with the chute and in gear connection with a deflector, whereby the deflector is rotated about the axis of the chute, and, incidentally, its position is also shifted radially, whereby the feed is gradually directed from the center of the silo to its walls in a uniform shower.

With the above and other objects in view, the invention consists in certain peculiarities of construction and combination of parts as will be fully set forth hereinafter with reference to the accompanying drawings and subsequently claimed.

In the drawings, Figure 1 represents a fragmentary sectional view of the top portion of a standard silo, having a discharge chute entering the same and equipped with an apparatus embodying the general features of my invention, parts being in section and other parts broken away to more clearly illustrate structural features.

Figure 2 is a detail face view of a star wheel utilized for imparting radial adjustment to a feed deflector.

Figure 3 is an enlarged fragmentary sectional elevation of the mechanism embodying the features of my invention; and

Figure 4 is a plan view of the same, with

parts broken away and in section, as indicated by line 4—4 of Figure 1.

Referring by characters to the drawings, A represents the top portion of a standard silo provided with a filling opening B of the usual type, and extending through this filling opening is a pipe or chute C, which chute extends downwardly to suitable mechanism whereby the cut feed is delivered by air pressure in a stream through the mouth of the chute into the central portion of the silo.

The chute is provided with an offset housing 1 having journalled therein a drive shaft 2, which drive shaft carries an impeller 3 provided with blades 3', which blades, in their rotation, project into the chute through an opening 4 in the rear wall thereof.

The drive shaft 2 also carries a worm 5 that is suitably encased in the housing 1 and said worm, and said worm meshes with a worm wheel 6 mounted upon a vertically disposed countershaft 7, which shaft at its upper and lower end is provided with suitable bearings that extend from the said housing. The lower end of the countershaft carries a pinion 8, which pinion is in mesh with the teeth 9 of a ring 10.

The ring is mounted upon an angle iron circular track 11 suitably secured to the discharge mouth D of the chute, through a plurality of anti-friction rollers 12, as best shown in Figure 3 of the drawings. The anti-friction rollers are mounted upon studs 13 that extend from the rotary ring 10, it being understood that the track 11 and rollers are suitably protected by a circular contact shield 14, which may constitute part of the ring, with its inner edge in close but free connection with relation to the walls of the chute. The ring 10 is also provided with an extension arm 15 which terminates in a hub 15'. The hub 15' has journalled therein a sleeve 16, which sleeve is secured to a star wheel 17. It is obvious that the star wheel and sleeve in some instances may be cast in one.

The sleeve 16 is in threaded union with a spindle 18, the inner end of which in this exemplification of my invention, loosely engages a pad 19 which forms part of the rear

- wall of a deflector or boot 20. The boot 20, at its upper heel portion, is pivoted to ears 21 that form part of the ring arm 15. The boot or deflector, as shown, is provided with parallel side walls and a curved bottom wall 5 which extends from the pivot point of the boot to its toe, it being understood that the position of the boot is such that its curved bottom face is always within the field of discharge of the chute.
- 10 The fingers of the star wheel, as best shown in Figures 1 and 2 of the drawings, are provided for engagement with tappet pins 22', which are carried by an oscillatory anchor plate 23, the said anchor plate being pivotally mounted upon an arm 24 that extends from the housing 1. An arm 25 extends rearwardly from the anchor plate, and said arm has secured thereto a cable 26, there being a similar cable 27' connected to the anchor plate in juxtaposition to the upper tappet pin. These cables are trained over guide sheaves 28 which are carried by the housing, and a guide sheave 28 is suitably fixed with relation to the silo, thus, said cables may be led down to a convenient position whereby they may be operated to shift the position of the anchor plate.
- 15 20 25

From the foregoing description, it is manifest that as the light and heavy particles travel through the chute, either under air pressure or gravity, the volume will impart rotation to the impeller 3, which, in turn, through its gear connections, will rotate the ring 9 and thus cause the deflector or boot 20, carried thereby, to revolve above the mouth of the chute.

In coordination with this movement, the discharge toe α of the boot is radially adjusted 40 with relation to the axis of rotation of the ring, whereby the ensilage is supported from approximately a central position with relation to the walls of the silo, radially to the boundary or side walls in a uniform stream, 45 thus insuring proper distribution.

This radial adjustment of the boot is effected by the fingers or teeth of the star wheel 17, engaging either one of the anchor pins 22 and 22'. If, for example, the anchor pin 22 has been manually adjusted by the cables 26 and 27' into the path of travel of the star wheel, the screw threaded connection between the spindle and star wheel will cause the toe α at the boot to move radially step by step from the axis of the chute mouth, and thus change the position of the discharge of the feed slightly with each rotation of the ring. Should it be desired to reverse the position of the toe α , after it has reached its 55 extreme outward discharge point, the anchor plate 23 is manually shifted so as to bring the tappet pin 22' into the path of travel of the star wheel, whereby the movement of the chute will slowly reverse from that position indicated in dotted lines in Figure 1, to

the position indicated in full lines in such figure.

While I have shown and described one complete mechanism in all its details to carry out the desired movements of the boot, it is apparent that such details may be changed from time to time without departing from the spirit of the invention, as defined in the claims.

I claim:

1. A distributing apparatus comprising a 75 delivery chute, an impeller having blades extending into the chute, a ring rotatably mounted with relation to the chute mouth, a gear connection between the ring and impeller, a boot pivoted to the ring, an arm extending from said ring, a star wheel carried by the arm, a spindle in threaded union with the star wheel for engagement with the boot, and a manually controlled oscillatory anchor having tappet pins adapted to be selectively 80 shifted in the path of travel of the star wheel.

2. A distributing apparatus comprising a delivery chute, a head rotatably mounted on the chute, an impeller having blades extending into the chute and rotated by the passage of material through the chute, means operatively connecting the impeller with the head for bringing about the rotation of said head, a boot rockably connected with the head, 90 means for rocking the head including a feed screw, a feed nut for actuating the screw, an operating wheel connected with the nut having a plurality of radially extending arms, a 95 rocking plate mounted at one side of the chamber having upper and lower tappet arms arranged on opposite sides of the axial center of said wheel, and means for shifting said member for bringing either of said tappet pins in the path of the arms of the wheel.

In testimony that I claim the foregoing, I have hereunto set my hand at Milwaukee, in the county of Milwaukee and State of Wisconsin.
